HIDE OR SKIN DRESSING TOOL

Filed April 5, 1939

UNITED STATES PATENT OFFICE

2,178,019

HIDE OR SKIN DRESSING TOOL

Oscar D. Knuteson, Katalla, Territory of Alaska

Application April 5, 1939, Serial No. 266,185

3 Claims. (Cl. 149—13)

This invention relates to a hide or skin dressing tool, and has for the primary object the provision of a device of this character which may be conveniently worn on a hand of a person without cramping the fingers or hand and which includes a scraping blade so arranged that desired pressure may be placed thereon by the fingers and a portion of the hand so that fat and like substance may be easily and quickly scraped from a hide or skin held in scraping position by the other hand of the person.

With these and other objects in view, the invention consists in certain other novel features of construction, combination and arrangement of parts to be hereinafter more fully described and claimed.

For a complete understanding of my invention, reference is to be had to the following description and accompanying drawing, in which:

Figure 1 is a perspective view illustrating a hide or skin dressing tool constructed in accordance with my invention.

Figure 2 is a vertical sectional view illustrating the same.

Figure 3 is an end view illustrating the device.

Referring in detail to the drawing, the numeral 5 indicates a blade having a slight arcuate curvature in a portion thereof and terminating in one end in a cutting or scraping edge 6. The remaining portion of the blade which is not curved is substantially straight and has formed on opposite edges thereof upstanding attaching flanges 7 apertured to receive bolts or like fasteners 8 which secure on the blade or the straight portion thereof a finger stall 9 consisting of an elongated block 10 having a flat lower face and an upper curved face and a straight front face in which are formed finger grooves 11.

The fasteners 8 also secure to the flanges 12 spaced arms 12 which extend rearwardly of the blade and include angularly related portions, as clearly shown in Figure 2, and are connected by a cross member 13 having upstanding ears 14 provided with slots 15 to receive an adjustable hand strap 16. The hand strap 16 is adapted to be placed across the back of the hand with the palm of the hand facing downwardly between the rearwardly extending arms 12 with the fingers or tip ends thereof engaging in the finger

grooves 11 of the finger stall 9. A hand strap 17 is secured to the upstanding flanges 7 of the blade and is adapted to pass over the backs of the fingers for aiding in retaining the fingers within the finger grooves of the finger stall 9. With the tool applied to the hand and fingers as described a person can place considerable pressure on the blade 5 so that fat and other substances may be thoroughly scraped from skins or hides while the latter are held in scraping position by the other hand of the person. This device can be worn on the hand with considerable comfort and will not be tiring or cramping to the hand.

It is believed that the foregoing description, when taken in connection with the drawing will fully set forth the construction and advantages of this invention to those skilled in the art to which such device relates so that further detailed description will not be required.

Having described the invention, what is claimed is:

1. A dressing tool comprising a blade having a scraping edge, a finger stall carried by said blade, and hand straps for retaining a person's hand in proper relation to the blade with the fingers in engagement with the finger stall.

2. A scraping tool comprising a blade having a scraping edge and provided with upstanding flanges spaced from the scraping edge, a finger stall mounted on the blade between said flanges and including finger grooves, a finger strap connected with said flanges and adapted to pass over the fingers of a person's hand with the fingers resting in said finger grooves, and means connected with said flanges for further connecting the blade with the person's hand.

3. A scraping tool comprising a blade having a scraping edge and provided with upstanding flanges spaced from the scraping edge, a finger stall mounted on the blade between said flanges and including finger grooves, a finger strap connected with said flanges and adapted to pass over the fingers of a person's hand with the fingers resting in said finger grooves, arms connected with said flanges and extending rearwardly of the blade and including angularly related portions, and an adjustable hand strap connected with said arms.

OSCAR D. KNUTESON. 50
